Primary Examiner — Bao-Yen T Nguyen*Assistant Examiner* — Emily Anna Saunders(57) **CLAIM**

The ornamental design for a sensory toy, as shown and described.

DESCRIPTION

FIG. 1 is a front, bottom, left side perspective view of the sensory toy, showing my new design;

FIG. 2 is a rear, top, right side perspective view thereof;

FIG. 3 is a bottom elevational view thereof;

FIG. 4 is a top elevational view thereof;

FIG. 5 is a left side elevational view thereof;

FIG. 6 is a right side elevational view thereof;

FIG. 7 is a front elevational view thereof; and,

FIG. 8 is a rear elevational view thereof.

The broken lines in the drawings show portions of the sensory toy that form no part of the claimed design.

1 Claim, 8 Drawing Sheets(56)
